**TUBULAR HOOD FOR ATTACHMENT TO A
FLASHLIGHT THEREBY ADAPTED FOR
TRANSILLUMINATION**

Antonino Araujo, Jr., Columbus, Ohio, assignor to
Abbott Laboratories, North Chicago, Ill.

Filed Apr. 5, 1973, Ser. No. 348,439

Term of patent 14 years

Int. Cl. D26—99, 02
U.S. Cl. D48—20 H

FIG.1

FIG.3

FIG.2

FIG.4

FIG. 1 is a perspective view of a tubular hood for attachment to a flashlight thereby adapted for transillumination and showing my new design thereof.

FIG. 2 is a side elevational thereof,

FIG. 3 is a top plan view thereof; and

FIG. 4 is a bottom plan view thereof, the top exterior portion of the casing being omitted for convenience of illustration.

I claim:

The ornamental design for a tubular hood for attachment to a flashlight thereby adapted for transillumination, as shown and described.
